(57) **CLAIM**

The ornamental design for an earphone, as shown and
described.

DESCRIPTION

FIG. 1 is a top, front, and left side perspective view of an
earphone showing the new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the drawings illustrate portions of
the earphone that form no part of the claimed design. The
long dash-short dash lines represent the boundary between
the claimed and unclaimed design and form no part of the
claimed design.
